VALVE GUIDE FOR WATER CLOSET

Joseph Grebmeier, Palo Alto, and Leonello Brunetti,
San Francisco, Calif.

Application August 5, 1954, Serial No. 448,055

8 Claims. (Cl. 4—57)

This invention relates to a valve guide means for a water closet. More particularly this invention relates to a self-centering means for guiding the rubber tank ball or outlet valve of a water closet to cause the same to register accurately with the outlet opening and to effectively and dependably shut off the water supply from the tank to the toilet bowl of a water closet when the tank has drained.

In water closets of the household variety, a unitary installation is provided which includes a toilet bowl and a tank at the rear of the bowl for holding a supply of water to flush the toilet bowl after use. Means are provided within the tank to empty a predetermined quantity of water from the tank into the bowl for flushing, to close the outlet valve automatically and to refill the tank to a predetermined level. A frequent source of difficulty is the fact that the rubber tank ball or outlet valve many times does not seat properly in the outlet and on the valve seat, thereby permitting continual leakage of water from the tank into the toilet bowl. Consequently water wasted and the sound of running water is annoying.

Heretofore, several expedients have been tried in an endeavor to correct this difficulty. Thus a spider or guide member has been provided for insertion in the tank outlet and a guide rod affixed to the valve which extends slidably through the spider. The spider and slide rod are supposed to serve as a guide. However, this structure has not been satisfactory in practice.

It is an object of the present invention to provide improved means of guiding and centering the tank outlet valve of a water closet.

Another object of the invention is to provide self-centering guide and alignment means for the outlet valve of a water closet which is simple in its construction and easily installed and is efficient and dependable in its operation.

These and other objects of the invention will be apparent from the ensuing description and the appended claims.

One form of the invention is illustrated by way of the example in the accompanying drawing in which:

Figure 1 is a view, partly in side elevation and partly in vertical section, showing a typical household variety of water closet having a typical flushing arrangement but also having the self-centering and valve guide means of the present invention.

Figure 2 is a fragmentary view in side elevation, on a larger scale than that of Figure 1, showing the tank outlet, a conventional rubber ball or outlet valve seated in the outlet, and the novel self-centering guide means of the present invention.

Figure 3 is a top plan view of the self-centering guide means of the present invention.

Referring now to the drawings and more particularly to Figure 1, a conventional household variety of water closet is shown and is generally designated by the reference numeral 10. The water closet 10 comprises the usual toilet bowl 11 having a hinged cover 12 and a tank 13

2

having a cover 14 which is removable to permit access to the interior of the tank. A tank outlet is provided at 15 through which the tank empties to flush the bowl 11 and it forms a valve seat 15a to seat an outlet valve 16. 5 The valve 16 is commonly referred to as a rubber tank ball owing to its generally spherical shape and rubber construction. It is usually hollow but has a bottom opening so as to fill with water to prevent it from floating because of buoyancy. The tank outlet 15, the valve seat 15a and outlet valve 16 may be of conventional construction, such as that shown.

Also shown are conventional tank inlet pipes 17 and 18, the latter being the outlet branch and terminating somewhat above the bottom of the tank 13; a hollow, spherical brass float 19, attached to an arm 19a for operating a tank inlet valve (not shown); and a bypass tube 25 having its outer open end within the upper end of an overflow pipe 26. Other conventional elements of the water closet comprise a pull rod 27 which is threaded at 20 its lower end into the tank outlet valve 16, a link 28 one end of which is slidably connected to the pull rod 27, a lever 29 rotatably connected to the other end of the link 28 and extending rotatably through the front wall of tank 13 and a handle 30 for operating the flushing apparatus manually.

Referring now to Figures 2 and 3 as well as to Figure 1, a self-centering guide structure is provided for the outlet valve 16 and is generally designated by the reference numeral 35. It comprises a spider 36 having three radial arms 37 spaced approximately 120° apart and having also a fourth arm 38 which is twisted through an angle of 90° and whose outer, elongated end portion is formed into a circular clamping ring 39. The ring 39 is provided with a bolt 40 and a nut 41. By means of the ring 39, the assembly 35 may be mounted on the overflow pipe 26, by loosening the nut 40, spreading the ring 39 until it will slide over the upper end of pipe 26 or about its sides, then adjusting to the proper level and tightening the bolt 40 and nut 41. Also, the clamping ring 39 will be rotated to a position such that the spider 36 is in axial alignment with the outlet 15.

As is most clearly shown in Figure 3, the spider 36 has a central portion which is formed with a hole 42 to slidably receive the pull rod 27. As is most clearly shown 45 in Figure 2, the outer end of each of the spider arms 37 is bent downwardly to provide a short, vertical tab portion 43 which is formed with a hole 43a to rotatably receive an eye 44 attached to an elongated, cylindrical weight or centering or guide member 45. In the construction shown, the weights 45 are elongated and cylindrical, and they may be made of brass, lead or any other suitable material which is preferably a material having a high density and which is resistant to corrosion by water. The shape of the guide members 45 may depart from cylindrical but it is preferably such as to have free sliding contact with the tank outlet valve 16 at its widest diameter shown at 50. As will be seen from an inspection of Figure 2, the guide members 45 terminate somewhat below the widest diameter or rim 50 of the tank outlet valve 16 55 when the latter is seated on the valve seat 15a. The point of suspension of each member 45, at 43a is such that, while it is hanging in normal vertical position it will just contact the rim or horizontal diameter 50 of the tank outlet valve 16. It will also be apparent from an inspection 60 of Figure 2 that the guide members 45 are free to swing outwardly in response to a radial outward force but, by reason of their mass, they will always tend to swing back to vertical position.

In operation the water closet 10 is flushed by manual 65 operation of the handle 30. Thus, when the handle 30 is rotated in the proper direction, the tank outlet valve 16 is lifted free of the valve seat 15a by means of the

lever 29, link 28 and pullrod 27. Water is, therefore, allowed to flow from the tank 13 through the outlet 15 into the toilet bowl 11. Meanwhile, the float 19 will follow the water downwardly, thereby opening the inlet valve and admitting water to the tank.

As is well known, it is then necessary that the outlet valve 16 drop by gravity and reseat itself firmly and accurately in the valve seat 15a, to cut off the outflow of water, terminate the flushing operation and restore the moving parts of the flushing system to their normal positions shown in Figure 1. Barring the possibility of a faulty tank inlet valve (which is not a frequent occurrence), the usual difficulty, and the critical part of the cycle of operation of a water closet flushing system, is proper reseating of the tank outlet valve on its valve seat so as to cut off the outflow of water and terminate flushing.

The self-centering, guide mechanism serves the purpose of insuring accurate and dependable alignment of the tank outlet valve with its valve seat, and it does so in the manner which will now be described:

During the initial portion of the operating cycle, while the tank outlet valve 16 is raised, and again during a later stage in the operating cycle, while the valve 16 is dropping, forces act on the pull rod 27 and/or on the tank outlet valve 16 which tend to rock the valve 16 laterally. As a result, the pull rod 27 may tend to bind in the eye at the outer end of the link 28, thereby holding the outlet valve 16 in up position and preventing seating of the valve 16. Or the valve 16 may drop onto the outlet 15 but in a position out of alignment with the valve seat 15a, thereby only partially closing the outlet 15.

The self-centering guide structure 35 of the present invention provides self-centering means in the form of the guide members 45. These guide members are yieldable, i. e. they are free to rock outwardly, and will, therefore, allow the valve 16 to rock to a limited degree. But the guide members 45 act at all times to restore the valve 16 to its proper position in accurate alignment with the valve seat 15a and outlet 15. This yieldable restoring force acts on the outlet valve 16 at all times, both during raising of the valve 16 at the commencement of the operating cycle, and while the valve is dropping into place. Binding of the pull rod 27 and misalignment of tank outlet valve 16 are, therefore, effectively and dependably prevented.

It will, therefore, be apparent that a self-centering guide means is provided for use in connection with the tank outlet valve of a water closet which is simple in its construction; which is easily mounted in a toilet of standard design and construction and is readily adjusted; which is simple in its operation; and which acts yieldably but effectively and at all times to maintain the tank outlet valve in alignment with its valve seat and to restore the same to a position of alignment should it temporarily depart therefrom in response to a sufficient force.

We claim:

1. A guide structure of the character described, comprising a support member adapted to be mounted in the tank of a water closet directly above the tank outlet and the tank outlet valve, and a plurality of guide members suspended from said support member, arranged at spaced intervals about the center of the support member, and connected thereto in such manner as to allow lateral rocking of the guide members in response to an outward radial force; said guide members being so arranged as to be substantially tangent to said outlet valve when the latter is properly seated in said outlet opening, being free to rock outwardly as the outlet valve ascends and descends during operation thereof, and having sufficient mass to restore the outlet valve to a position of axial alignment with the outlet opening and to seat the outlet valve accurately in such opening.

2. A guide structure of the character described, comprising a support member adapted to be mounted in the

tank of a water closet directly above the tank outlet and the tank outlet valve, and a plurality of guide members suspended from said support member, arranged approximately equi-angularly about the center of the support member, and connected thereto in a manner to allow lateral rocking of the guide members in response to an outward radial force, said guide members being so arranged as to be substantially tangent to and in sliding contact with said outlet valve when the latter is properly seated in said outlet opening and while it is moving up and down during use, being free to rock outwardly as the outlet valve so moves, and having sufficient mass to restore the outlet valve to a position of axial alignment with the outlet opening and to seat the outlet valve accurately in such opening.

3. A guide structure of the character described, comprising a support member adapted to be adjustably mounted on the overflow pipe of the tank of a water closet and directly above the tank outlet opening and the tank outlet valve, and a plurality of cylindrical guide members each of substantial mass suspended from the support member to swing freely therefrom and to lie normally tangent to a cylindrical surface developed by vertical movement of the tank outlet valve during the flushing cycle.

4. A guide structure of the character described for guiding the tank outlet valve of a water closet to seat the same accurately in the tank outlet, said structure comprising a spider having a plurality of radial arms located in a common plane and spaced approximately equi-angularly with reference to a central axis perpendicular to such plane, said spider being formed with a central, axial opening to slidably receive the pull rod of a tank outlet valve, means for adjustably mounting said spider on the overflow pipe of a water closet tank, a guide member of elongated, cylindrical shape and relatively large mass freely suspended from the outer end of each arm of the spider so as normally to hang vertically when the spider is in a horizontal plane and to swing outwardly in response to an outward radial force, said guide members being arranged to be in sliding contact with said tank outlet valve as it ascends and descends during the course of operation.

5. A water closet flushing system comprised of a tank for holding water to supply a toilet bowl to flush the same, inlet means including a tank inlet valve and means for automatically opening the inlet valve to admit water to the tank when the water therein is below a predetermined level and to close the inlet valve when the water is at said predetermined level, a tank outlet and a valve seat therein, a tank outlet valve for seating on such valve seat to close the tank outlet, means for operating the outlet valve, including a pull rod for raising the outlet valve from the valve seat and permitting the outlet valve to drop onto the valve seat, and guide means for said outlet valve comprising a plurality of guide members of substantial mass and means freely suspending the same so as to lie normally in vertical position tangent to the outlet valve during the course of its vertical movement and to rock outwardly in response to a sufficient force so rocking the outlet valve and to restore the outlet valve by reason of their mass.

6. A water closet flushing system comprising a tank for holding water to supply a toilet bowl to flush the same, an overflow pipe in such tank, inlet means including a tank inlet valve and means for automatically opening the inlet valve to admit water to the tank when the water therein is below a predetermined level and to close the inlet valve when the water is at said predetermined level, a tank outlet and a valve seat therein, a tank outlet valve for seating on such valve seat to close the tank outlet, means for operating the outlet valve including a pull-rod for raising the outlet valve from the valve seat and permitting the outlet valve to drop onto the valve seat, and guide means for said outlet valve comprising a plurality of guide members of cylindrical shape and sub-

stantial mass, and a spider adjustably mounted on said overflow pipe, the arms of said spider freely suspending said guide members so as to lie normally in vertical position tangent to and in sliding contact with the outlet valve during the course of its vertical movement and to rock outwardly in response to a sufficient force so rocking the outlet valve and to restore the outlet valve by reason of their mass.

7. A valve guide for the outlet valve of a water closet comprising a suspension member adapted to be mounted above and in axial alignment with the outlet of a water closet tank, and a plurality of elongated weights each of large diameter compared to the diameter of the valve stem of a water closet, each said weight being suspended at one end to swing without hindrance except for inertia through a wide arc in response to a lateral force, said weights being arranged to be substantially tangent to the cylinder described by the outlet valve of a water closet as the same is operated; said weights offering resistance to lateral displacement of the outlet valve of a water closet and providing a restoring force substantially entirely by reason of their mass.

8. Water closet flushing apparatus comprising a tank,

means for admitting water to the tank to a predetermined level, a flushing outlet at the bottom of the tank, an outlet valve for closing said flushing outlet, a stem for said valve in the form of a rod of small diameter, means 5 slidably mounting said stem to allow vertical movement of the valve in axial alignment with said outlet, a plurality of elongated weights each of much greater diameter and much greater mass than said stem and means suspending said weights so as normally to hang in vertical position substantially tangent to the cylinder described by said valve as it operates; said suspending means permitting free swinging of said weights in the manner of pendulums and offering substantially no resistance to such swinging movement; the masses of said weights providing substantially the only restoring force serving to restore said valve to its normal position in axial alignment with said outlet when a lateral force tends to swing the valve laterally.
